UNITED STATES PATENT OFFICE.

FREDERIC K. PLYMPTON, OF WELLESLEY, MASSACHUSETTS, ASSIGNOR TO PLYMPTON MANUFACTURING COMPANY, OF BOSTON, MASSACHUSETTS, A CORPORATION OF MASSACHUSETTS.

TAG.

1,156,036.

Specification of Letters Patent.

Patented Oct. 5, 1915.

Application filed May 26, 1910. Serial No. 563,556.

To all whom it may concern:

Be it known that I, FREDERIC K. PLYMPTON, a citizen of the United States, residing at Wellesley, in the county of Norfolk, State 5 of Massachusetts, have invented a certain new and useful Improvement in Tags, of which the following is a specification, reference being had therein to the accompanying drawings.

10 The invention consists in an improved tag which is applicable either as a shipping tag, baggage-tag, price-tag, or for general purposes as a label.

The invention has reference more particularly to the means of attaching to the tag or label a string or wire for securing the tag or label to the package or article with which it is to be connected.

Objects of the invention are to produce 20 a tag or label of novel and improved construction. Also, to produce one which may be manufactured economically and at a high rate of speed by automatic machinery without manual intervention. Also, to produce 25 a tag or label which will pack better and in less space than shipping tags of the character now in use having attaching strings combined therewith.

Briefly stated, the invention provides a 30 tag or label, hereinafter generally termed simply a tag, having applied to the same a narrow strip or piece of sheet material of U-shape, clasping a marginal portion of the tag or label proper and an intermediate portion 35 of the length of the string or wire and clamping the string or wire within its bend or bight so as to prevent longitudinal movement of the string or wire, with its respective limbs permanently secured at intermediate 40 points in their lengths to the opposite surfaces of the tag or label proper.

A feature of the invention consists in the 45 special form and relative disposition of the respective limbs of the sheet-metal strip or piece and of the riveting portions of the same.

By the terms "cord" and "string" as employed herein I intend to include a wire or other flexible material constituting an 50 equivalent thereof for attaching purposes.

Embodiments of the invention are shown in the drawings, Figure 1 showing one side of a tag constructed in accordance with the invention, and Fig. 2 showing the other side 55 thereof, while Fig. 3 shows the tag in sec-

tion in the plane of the dotted line 3, 3, of Fig. 1, one form of the sheet-metal strip or piece being employed. Fig. 4 shows one side of a tag having a second form of sheet-metal strip or piece, Fig. 5 the other side 60 thereof, and Fig. 6 a section in the plane of the dotted line 6, 6, of Fig. 4. Fig. 7 is a side view, and Fig. 8 a section in the plane of line 8, 8, of Fig. 7, showing another form of embodiment of certain portions of the 65 invention. Fig. 9 is a side view, and Fig. 10 a section in the plane of line 10, 10, of Fig. 9, showing still another form. Figs. 11 and 12 are views showing the crimping of the 70 sheet-metal strip or piece to prevent the string or wire from drawing out of the bend or bight thereof.

Having reference to the drawings,—in the different views the piece of material constituting the tag proper is designated 1, the attaching string being in each case designated 2. The piece or strip of sheet-metal by which the said string is secured to the tag proper is designated 3 in Figs. 1, 2 and 3, and 3^a in Figs. 4, 5 and 6. The tag proper 80 will be composed of paper-material, cloth, or any other material suitable to be employed for the purposes of a tag or label. The size or shape of the same will vary in practice. The string will be of convenient 85 length for use in securing the tag or label to the article or package in connection with which it is desired to employ the tag or label. Only a short portion thereof is shown 90 in the drawings.

In Figs. 1, 2, 3, the metal strip or piece 3 is of uniform width throughout its length. It is much narrower than the piece of material 1. Being bent or doubled upon itself, with the string 2 inclosed in its bend or bight, and with a marginal portion of the tag proper between its respective limbs, the latter lie snugly and smoothly against the two surfaces of the tag proper, and the string is retained at one edge of the tag 100 proper, against such edge. The riveting of the said metal strip or piece 3 to the tag proper is effected in Figs. 1, 2, 3, by punching one or more holes 3^b, 3^b, through the limbs of the sheet-metal strip or piece without, however, the removal of any portion of the metal, the metal which is displaced in forming a hole being split and the split portions being caused to stand up at an angle 105 from the plane of the main portions of the 110

strip or piece. The upstanding portions around the different holes are like what in shop-terms frequently are called burs. They are driven into and through the material of the tag proper, and clenched. In the drawings the upstanding metal at each hole is represented as divided to form four points arranged in a circular series, this result being secured by shaping suitably the devices which are employed for making the holes. By an obvious change in the said devices a different number of points may be produced. Preferably the holes and burs of one limb of the sheet-metal strip or piece are alternated in position with respect to those of the other limb thereof, so that those of one limb dodge or miss those of the other limb. The number and arrangement of the holes and sets of burs on the respective limbs of the metal strip or piece may be varied as desired, and to meet particular considerations and requirements.

In Figs. 1, 2 and 3, one limb of the bent metal strip or piece is formed with two somewhat widely separated holes and series of burs, these last being set and riveted in the material of the tag proper from one side of the latter, and the other limb is formed with one hole and series of burs which last are set and riveted in the material of the tag proper, from the other side of the latter, intermediate and in line with the two holes of the limb first described, all three holes and series of burs being disposed in the same straight line extending in the direction of the length of the tag proper.

Figs. 4, 5, and 6 show a form of the invention having certain advantages over the form above described and shown in Figs. 1, 2 and 3. In Figs. 4, 5 and 6 one limb of the metal strip or piece 3^a is a simple straight piece having a single hole 3^b and a series of burs set in the material of the tag proper from one side of the latter. The other limb of the said piece or strip is forked or U-shaped, the branches of the same being separated to the extent of the width of the limb first described, and the said branches fitting against the other surface of the tag proper in such manner that the three parts of the strip or piece of sheet-metal alternate in their arrangement, as clearly indicated by the full and dotted lines in Figs. 4 and 5. Each of the branches of the U-shaped limb is shown formed with a single hole 3^b and a corresponding series of burs which are set and riveted in the material of the tag proper from the side of the latter at which the said U-shaped limb is located. In the case of the different forms of embodiment of the invention, the number of holes and series of burs in the respective limbs of the sheet-metal piece or strip may be greater than that shown, if found or deemed necessary.

65 In the form of the invention which is

shown in Figs. 7 and 8, one limb of the sheet-metal piece or strip, 3^c, has a simple hole 3^d punched therein, the other limb or end-portion being formed with a hole 3^e and a series of burs, which last are driven 70 through the material of the tag proper and passed through the hole 3^d, their tips being clenched or riveted down upon the outer side of the limb in which such hole 3^d is formed.

In the form of the invention which is 75 shown in Figs. 9 and 10 a simple hole is punched in each limb of the sheet-metal piece or strip 3^f, and in this instance a hole is made through the material of the tag proper. A rivet 3^g, which in this instance is 80 tubular, is set in the holes of the respective limbs and the tag proper, and clenched or riveted to secure the whole together.

The bend or bight, or as it might be termed the back, of the U-shaped sheet-metal piece or strip is shown transversely curved in Figs. 1, 2, 4, 5, 7, 9 and 11. The curvature is such as to present a convex surface next the string 2. It turns the edges of the sheet-metal away somewhat from the 90 string, so as to obviate bending of the string around the sharp corners, and the resulting tendency to chafe or cut the string. The portion in question of the sheet-metal piece or strip is reduced in width by the crimping 95 or bending which produces the transverse curvature, so as to form a neck where the string tends naturally to remain.

Figs. 11 and 12 show the crimping, at 3^h, of the metal strip or piece to securely hold 100 the string from pulling endwise out from the bend or bight of the said strip or piece.

I claim as my invention:—

1. The combination with the tag or label proper, and the attaching string, of the U-shaped sheet-metal strip or piece clasping the string and a marginal portion of the tag or label proper within its bend or bight, having its respective limbs formed each with one or more burs intermediate the said bend or bight and the end of the limb which are set in the material of the said tag or label proper from the opposite faces of the latter and clenched, the burs of the said limbs being alternated in position so that those of one limb dodge those of the other.

2. The combination with the tag or label proper, and the attaching string, of the U-shaped piece or strip clasping a marginal portion of the tag or label proper and an intermediate portion of the length of the string and clamping the string within its bend or bight, with its respective limbs permanently secured at intermediate points in their lengths to the opposite surfaces of the tag or label proper.

3. The combination with the tag or label proper, and the attaching string, of the U-shaped strip or piece clasping a marginal portion of the tag or label proper and in-

closing and clamping the said string within its bend or bight, having its respective limbs formed each with one or more burs intermediate said bend or bight and the end 5 of the limb which are set in the material of the said tag or label proper from the opposite faces of the latter and clenched, the said strip or piece being thereby permanently attached to the tag or label proper with its 10 limbs held in firm contact with the surfaces

of the tag or label and prevented from spreading apart so as to loosen the grip upon the string.

In testimony whereof I affix my signature in presence of two witnesses.

FREDERIC K. PLYMPTON.
